(57) **CLAIM**

We claim the ornamental design for a cable housing, as shown and described.

DESCRIPTION

FIG. 1 is a front elevational view of the cable housing; FIG. 2 is a rear elevational view thereof;

FIG. 3 is a top view thereof;

FIG. 4 is a bottom view thereof;

FIG. 5 is a left side elevational view thereof;

FIG. 6 is a right side elevational view thereof;

FIG. 7 is a front, left, top perspective view thereof; and, FIG. 8 is a rear, right, top perspective view thereof.

The broken lines in the drawings are for illustrative purposes only and form no part of the claimed design.
